UNITED STATES PATENT OFFICE

2,479,550

TEMPORARY ERECTION FRAMING

James S. Barth, Chicago, Ill., assignor to Chicago Bridge & Iron Company, a corporation of Illinois

Application February 7, 1946, Serial No. 646,172

2 Claims. (Cl. 248—354)

1

This invention relates to a temporary erection framing to be used for supporting objects preparatory to assembling said objects. Erection framing is often necessary in construction work to support the component parts of objects while they are being assembled. One of the places in which such erection framing may be used is in the assembling of floating roofs to be used in floating roof tanks. It has formerly been the practice to erect the shell of the tank and then assemble the roof within the shell on framing resting on the floor of the tank. This framing was formerly composed of ordinary wooden beams. Such a procedure, however, has the disadvantage of being expensive, as it took a lot of time to place the beams properly and then to remove them after the roof had been assembled.

In order to enable workmen to build floating roofs and other structures more quickly and with less trouble, it was necessary that some other type of temporary erection framing be used. The present framing has the advantage of being easy to assemble, taking up very little space, and being readily disassembled. The new temporary erection framing is made up of several pieces of equipment that are light in weight and not bulky. By the use of the new erection framing much time and labor can be saved, and a better job can be done. The framing can be used over and over again, and can be easily transported from one job to another. Since using this temporary erection framing the jobs have been completed faster and with less difficulty and less expense.

The new erection framing comprises individual pieces of equipment, with each piece comprising a pedestal; an adjustable, substantially vertical post member to be held by said pedestal; a support for a removable base member, such as a wooden beam; and means for locking said post member on the pedestal to maintain the support at a desired elevation. In a preferred embodiment the pedestal comprises a substantially equilateral triangle having sections of pipe at each apex thereof with all the pipes substantially aligned with the center of the triangle. The pipe member may be held within any pipe section to extend upwardly, and the opposite side of the triangle will then serve as the base of the pedestal. The pipe member may be locked at a desired height by any means desired. The top end of the pipe member will hold an upwardly extending forked member with the pipe member extending through the base of the fork so that base members may be held within the fork on either side of the pipe member.

2

The invention will be described as related to the embodiment set out in the accompanying drawings. Of the drawings Fig. 1 is a fragmentary plan view of the shell of the floating roof tank with the temporary erection framing in place for assembling a floating roof; Fig. 2 is a vertical section taken along line 2—2 of Fig. 1; Fig. 3 is a vertical section taken along line 3—3 of Fig. 2; Fig. 4 is a vertical section taken along line 4—4 of Fig. 1; Fig. 5 is a front elevation of one of the pedestals and pipe members; Fig. 6 is a side elevation of said pedestal and pipe member; Fig. 7 is a plan view of said pedestal and pipe member; Fig. 8 is a vertical section showing a portion of the shell of a floating roof tank with a stirrup attached thereto; and Fig. 9 is a vertical section taken along line 9—9 of Fig. 8.

Each unit of the temporary erection framing comprises a pedestal 10, an upwardly extending pipe member 11, and an upwardly extending U-shaped member 12 mounted on the top portion of the pipe member 11.

Each pedestal 10 has the shape of an equilateral triangle with pipe sections 13 at each apex of the triangle and with pieces of angle iron 14 connecting the pipe sections 13 to form the equilateral triangle. All pipe sections are substantially aligned with the center of the triangle and bisect the angles formed by the sides of the triangle.

The pipe member 11 has an outer diameter smaller than the inner diameter of the pipe sections 13. The pipe member may be held within any pipe section 13 with the opposite side 14a of the triangle serving as the base of the pedestal. The pipe member 11 may be held at any desired elevation and a nut 15 may then be welded to the pipe member 11 just above the topmost pipe section 13. This nut prevents the pipe member from sliding further within the pipe section.

The U-shaped member 12 which serves as a fork has a hole in its bottom plate through which the pipe member 11 extends with the member welded to the U-shaped member. Wooden beams 16 may be held in place on either or both sides of the top of the pipe member 11, and may be fastened by nails 17 driven through holes 18 provided in the sides of the U-shaped member. It is preferred that the nails be not driven all the way in so that they can be easily withdrawn (Fig. 5). The bottom portion of the U-shaped member 12 is preferably provided with upwardly extending sharp points 19 which may be formed by punching a hole through the base with a square punch.

These points help anchor the wooden beams 16.

When using such temporary erection framing for erecting floating roofs the shell 20 and bottom 21 of the tank are assembled. Stirrups 22 are welded to the shell 20 at a desired elevation to hold the outer ends of substantially radial beams 16. These stirrups have flat bottoms 23 and upwardly extending side portions 24 and 25. One of the side portions 24 is higher than the other side portion, 25. The high portion has an edge sloping toward the shell, while the other side portion 25 has an edge sloping away from the shell. The shorter side portion 25 is provided with a hole 26, through which a nail may be driven to hold its wooden beam 16.

The pedestals 10 and the pipe members 11 are then placed at their proper locations, and the pipe members adjusted to the desired height. As pointed out the pipe members are held at their desired elevation by welding nuts 15 on each pipe member. The wooden beams 16 are then placed in the U-shaped members 12 and nailed in place. A typical assembly showing one arrangement of the temporary erection framing is shown in Fig. 1. Any other arrangement may of course be used, depending upon the particular structure to be assembled. As the pedestals 10 are substantially planar and stand on edge, adjacent pedestals for any beam 16 may be turned at right angles to each other in order to give the structure stability.

After the floating roof or other structure has been assembled the pedestals 10, pipe members 11, wooden beams 16, and stirrups 22 are removed. As each portion of the framing is relatively small the disassembling of the framing is simple. The framing may then be transported to another job and used over and over again. Any apex of each pedestal 10 may be used to hold a pipe member 11 so that if one pipe section 13 is damaged the pedestal is not ruined, but can be used with either of the other two pipe sections to hold the pipe member.

Having disclosed my invention as related to

one embodiment of the same, it is my intention that the invention be not limited by the details of description unless otherwise specified, but rather be construed broadly within its spirit and scope as set out in the accompanying claims.

I claim:

- Temporary erection framing comprising: a pedestal, an adjustable substantially vertical pipe member to be held by said pedestal, a support for a removable beam member mounted on said pipe member, said support including an upwardly-extending forked member attached to the pipe member with said pipe member extending through and beyond the base of the forked member whereby beam members may be held within the fork on either side of and spaced by the pipe member, and means for locking said pipe member on the pedestal to maintain said support at a desired elevation.
- Temporary erection framing comprising: a pedestal having the shape of a substantially equilateral triangle, a pipe at each apex of the triangle, said pipes being in the plane of the triangle and being substantially aligned with the center of the triangle, an adjustable substantially vertical pipe member insertable through any of said pipes, the side of the triangle opposite the apex at which the pipe member is inserted serving as a base for the pedestal, a support for a removable beam member mounted on the pipe member and means for locking said pipe member on the pedestal to maintain said support at a desired elevation.

JAMES S. BARTH.
